(57) **CLAIM**

The ornamental design for pocket, as shown and described.

DESCRIPTION

FIG. 1 is a front perspective view of a pocket, showing my new design, shown in the opened condition;

FIG. 2 is a front elevational view of the invention, the pocket cover in a closed position;

FIG. 3 is a rear elevational view of the invention, the pocket cover in the closed position;

FIG. 4 is a right-side elevational view of the invention, the pocket cover in the closed position;

FIG. 5 is a left-side elevational view of the invention, the pocket cover in the closed position;

FIG. 6 is a top plan view of the invention, the pocket cover in the closed position; and,

FIG. 7 is a bottom plan view of the invention, the pocket cover in the closed position.

The dashed lines shown in the drawings represent a stitching line.
